CLAIM

The ornamental design for a cooking apparatus as shown and described.

DESCRIPTION

FIG. 1 is a first perspective view of a cooking apparatus showing our new design.

FIG. 2 is a second perspective view thereof in a first configuration.

FIG. 3 is a third perspective view thereof in a second configuration.

FIG. 4 is a first top view thereof in the second configuration; and,

FIG. 5 is a second top view thereof in the first configuration. The broken lines shown in the Figures show environment and portions of the cooking apparatus that form no part of the claimed design. Any part of the cooking apparatus not shown in the Figures forms no part of the claimed design. The shade lines in the Figures show contour and do not claim surface ornamentation or treatment.
